UNITED STATES PATENT OFFICE

94,503

DESIGN FOR A WASHING MACHINE CASING

Francis W. McGrath, West Bend, Wis., assignor
to The Barton Company, West Bend, Wis., a
corporation of Wisconsin

Application January 18, 1934, Serial No. 50,441

Term of patent 7 years

To all whom it may concern:

Be it known that I, Francis W. McGrath, a citizen of the United States, residing at West Bend, in the county of Washington and State of Wisconsin, have invented a new, original, and ornamental Design for a Washing Machine Casing, of which the following is a specification, reference being made to the accompanying drawing, forming a part thereof, in which Fig. 1 is a perspective view of a washing machine casing showing my new design; and Fig. 2 is a sectional detail view taken on the line 2—2 on Fig. 1.

The dominant feature of the design resides in the particular contour of the leg and the provision of an embossed portion of similar contour therein and the providing of a plate within the embossed portion and corresponding to the configuration thereof.

I claim:

The ornamental design for a washing machine casing, as shown and described.

FRANCIS W. McGRATH.
